UNITED STATES PATENT OFFICE.

HAROLD L. HANSON, OF BUTTE, MONTANA, AND MARION B. SAWYER, OF EDMONDS,
WASHINGTON.

PROCESS OF BURNING TREE-STUMPS.

1,352,261.

Specification of Letters Patent.

Patented Sept. 7, 1920.

Application filed November 9, 1918. Serial No. 261,843.

To all whom it may concern:

Be it known that we, HAROLD L. HANSON and MARION B. SAWYER, citizens of the United States, residing respectively, at 5 Butte, in the county of Silverbow and State of Montana, and at Edmonds, in the county of Snohomish and State of Washington, have invented new and useful Improvements in Processes of Burning Tree-10 Stumps, of which the following is a specification.

The present invention comprehends generally improvements in stump destroyers and more particularly relates to a process 15 of burning tree stumps.

The invention has for its principal object to provide a process of the above mentioned character which consists in boring passages within the stump, then building a fire there-20 in and finally forcing a draft of air through one of the passages for insuring of an effective internal combustion and the consequent burning of the stump so as to render the ground available for cultivation.

More particularly, the invention consists 25 in the provision of a process of the character mentioned wherein a piece of red hot charcoal is dropped into one of the passages and then air is forced through the 30 said passage and the other passages to form charcoal about the passages, which is consumed, and on the continued forcing of air the fiber immediately adjacent the charcoal is prepared so that charcoal may eventually 35 be produced and all of the charcoal ultimately consumed insuring of the burning of the stump from the center of the base to the top and outer surfaces and at the base thereof.

Other objects as well as the nature, characteristic features and scope of this invention will be more readily apparent from the following description taken in connection with the accompanying drawings and 45 pointed out in the claims forming a part of this specification.

The invention is clearly illustrated in the accompanying drawings, in which:

Figure 1 is a vertical sectional view of 50 the stump properly bored and with an air conducting pipe attached thereto and in elevation.

Fig. 2 is a top plan view of the stump, and

Fig. 3 is a horizontal sectional view taken 55 on line 3-3 of Fig. 1.

Similar characters of reference are employed in all of the above described views, to indicate corresponding parts.

Referring now, more particularly, to the 60 accompanying drawings, there is illustrated a tree stump 1 which is preferably first bored centrally and vertically to provide an air passage 2 the bottom of which constitutes a fire or combustion chamber 3. 65 The bottom of the fire chamber is positioned adjacent the base of the stump while the stump is further provided with a plurality of converging flues 4 preferably down- 70 wardly inclined which extend from the outer surface of the stump and at a point above the surface of the ground and above the visible branch roots and communicate with the passage 2 adjacent the fire chamber 3. A fire 5 is now started in the chamber 3 and preferably consists of a piece of 75 red hot charcoal which is dropped through the passage 2 into the chamber 3 while an air conducting tube is now fitted to the top of the passage 2 so that the air may be 80 forced down through the passage 2 upon the fire 5 while the bores or flues insure of the ignition of the fiber about the passages and flues which produces charcoal, and on the continued application of air the outer 85 or adjacent surfaces of the charcoal will be consumed while the continued burning prepares the fiber behind the charcoal for 90 burning so that more charcoal will be produced all of which is ultimately consumed. 95 Attention is particularly directed to the arrangement of the passage 2 and the flues 4 which insure of the proper and effective combustion centrally of and at the base of the stump causing an equal burning from 95 the center of the base to the top and outer surfaces and at the base of the stump. However, if one portion of the trunk is being consumed faster than the other the adjacent flue may be stopped by a plug of clay 100 or other material so as to retard the draft through such flue or passage.

It is believed in view of the foregoing description that a further detailed description of the process is unnecessary. It is also 105 believed that the advantages will be readily apparent. However, by the employment of this process it is to be appreciated

that the ground may be quickly and cheaply cleared of stumps and thereby render available for cultivation vast acres of cut over timber lands which would otherwise be untillable.

5. What is claimed is:

1. The process for burning tree stumps, which consists in providing a vertical air passage substantially in the center of the 10 stump, then providing a plurality of flue passages communicating with the air passage and opening on the sides of the stump, then starting a fire in the air passage, and finally forcing a draft of air into the air 15 passage and out through the flues.

2. The process for burning tree stumps, which consists in providing a substantially

central vertical air passage in the stump, then forming flue passages opening onto the periphery of the stump and communicating 20 interiorly with the air passage, then starting a fire in the bottom of the air passage, then forcing a draft of air into the air passage and out through the flue passages, and finally plugging such air passages as the 25 fire seems to follow, thereby causing the draft to pass out of the remaining passages and thus direct the fire in their direction, so that a uniform burning of the stump may be had.

30 In testimony whereof we affix our signatures.

HAROLD L. HANSON.
MARION B. SAWYER.
